CARBURETOR

Louis De Marco, Cleveland, Ohio, assignor of
fifteen per cent to Percy A. Secor, Cleveland,
Ohio

Application May 20, 1932. Serial No. 612,534

6 Claims. (Cl. 261—52)

This invention relates in general to carburetors for automobiles and other internal combustion engines which carburetors effect vaporization of gasoline or other fuels and the mixing of the vaporized fuel with a suitable amount of air to obtain high-power explosions in the cylinders of the engine, and more particularly to suction carburetors such as extensively used for automobile engines. It is well known that the best results are obtained when the proportions of fuel and air in the mixture are such that complete combustion of all the gasoline in the mixture takes place at the proper time leaving no unburned parts to be wasted. It is also well known that this desirable result is difficult of attainment with suction type of carburetors. Thus, when the speed of the engine increases, the suction produced increases in proportion. Increased suction proportionally increases the amount of gasoline sucked from the gas nozzle of the carburetor. On the other hand, increased suction does not proportionally increase the amount of air passing through the air passage and consequently, at the higher speeds of the engine, the mixture will be too rich in gasoline or fuel, and therefore much waste, accumulation of carbon, interference with the proper lubrication of the cylinder walls, and fouling of spark plugs will occur.

When driving at medium speeds, say coasting range, or while going down hill comparatively little power is needed. Under such conditions economy and smooth performance of the engine call for a rather lean mixture, whereas, hard pulling of the engine at low speeds for instance while climbing a hill, must be met with a slightly richer mixture.

The primary object of the present invention is to provide means for controlling the amount of air drawn into the mixture chamber so that the proper amount of air will be automatically fed into the carburetor and mixed with the gas to form the gas and air mixture most efficient under the existing conditions of speed etc.

A further object of the invention is to provide a valve arranged in the air intake of the carburetor and controlled by the suction of the engine, for feeding a correspondingly increased volume of air into the mixing chamber when the suction of the engine increases.

A still further object of the invention is to couple the automatically actuated control of the valve in the air intake with the throttle valve of the carburetor to effect partial control of the valve in the air intake by the throttle. Such par-

tial control is necessary while the engine is running under conditions, where comparatively little power is required and the suction of the engine is substantial.

With these and other objects in view the invention consists in the construction and novel combination of parts fully described hereinafter, illustrated, in the accompanying drawings, and pointed out in the claims appended hereto, it being understood that various changes in the form, proportion, size and minor details of construction within the scope of claims, may be resorted to without departing from the spirit of the invention.

In the drawings showing an exemplified form of a carburetor embodying the invention:

Figure 1 is a side elevation of a carburetor according to the invention;

Figure 2 is a longitudinal vertical section view through the carburetor shown in Figure 1;

Figure 3 is a sectional view on line 3—3 of Figure 2;

Figure 4 is a sectional view on line 4—4 of Figure 1;

Figure 5 is a sectional view on line 5—5 of Figure 4;

Figures 6, 7, 8 and 9 show diagrammatical views of the positions of the valves, the throttle valve and the air intake control valve at different speeds of the engine. Thus

Figure 6 shows the starting position of said valves;

Figure 7 the medium speed position of said valves;

Figure 8 the high speed position of said valves; and

Figure 9 the high power position of said valves at relatively low speed.

The vertical type of carburetor A illustrated herein embodies three main parts, the gasoline or float chamber B, the barrel or mixing chamber C and the air intake D. The carburetor A is split horizontally as at 2, thus providing an upper part 3 which forms a cover member for float chamber B arranged in a lower part 4. A float 5 within chamber B hingedly attached to upper part 3, as at 50 controls the movements of needle valve 6 in inlet passage 7 of a valve body 8 for maintaining the gasoline in chamber B at a predetermined level. An inlet passage 9 adjacent a removable strainer 10 and in communication with a fuel container not shown feeds gasoline into passage 7, from whence it flows into chamber B whenever the float 5 drops sufficiently to open valve 6.

Float chamber B communicates with the barrel or mixing chamber C, through a spray nozzle 11 threadedly secured within and extending through a passage 12 formed in the lower part 4 of the carburetor. Nozzle 11 is formed with a lateral passage 15 adjacent its lower end in alinement with and forming a continuation of a short passage 17 formed in the bottom wall of chamber B. The desired charge of gas will thus be sucked from chamber B through passages 17 and 15 and thence out through the central opening 16 in nozzle 11 into mixing chamber C. The customary idling jet 20 also draws fuel from chamber B upwardly and discharges into barrel chamber C through port 21 arranged with its outlet end adjacent the edge of the common butterfly throttle 22, so that it operates only when said throttle is slightly opened.

An air intake D communicating with barrel chamber C furnishes the necessary air, when the suction of the engine creates a vacuum in barrel chamber C, and a vacuum controlled air valve 23 of common butterfly type controls the amount of air flow. Valve 23 is actuated by a piston 24 arranged within a cylinder 25, on upper part 3 of carburetor A. This cylinder communicates through passage 26 with barrel chamber C just above butterfly throttle 22 for continuous exposure to the suction of the engine. A downwardly extending piston rod 27 on piston 24 and preferably integrally formed therewith is guided in a longitudinally slotted sleeve on extension 28 of cylinder 25 and this piston rod is coupled with valve 23. Thus piston rod 27 is slotted at 29 for engagement with a lever 30 pivotally mounted on shaft 31 of air valve 23 and yieldingly secured thereto by means of a spring 33' attached at one end to an extending arm 34 of said lever and at its other end to a clamp 51 rigidly secured to the shaft 31, to permit of slight relative movement of lever 30 with respect to shaft 31 for a purpose later to be described. The free end 35 of lever 30 is formed with a flat circular enlargement 36 which extends through slots 37 in extension 28 of cylinder 25 and thence into slot 29 for actuation during shifting of piston 24 and its piston rod 27. Piston 24 is yieldingly forced in a downward direction by means of a compression spring 38 arranged within cylinder 25 and seated between piston 24 and the top wall 39 of said cylinder, a sleeve like member 40 serving as a guide for the spring to prevent buckling when under compression.

The automatic actuation of air valve 23 by the suction of the engine is partially limited by throttle valve 22 to prevent unrestricted opening of air valve 23, except when valve 22 is fully open. Thus a lever 43 rigidly attached to shaft 41 of throttle valve 22 is pivotally connected to a lever 45 by means of a connecting rod 33, the free end of lever 45 being in turn pivotally connected to the part A of the carburetor. Lever 45 is formed with a bifurcated outer end 49 which slidably embraces the piston rod 27, the latter being provided with a flange 48 at its lower end for limiting the upward movement of piston 24, when the forked shaped end 49 of the lever 45 engages with flange 48. It will of course be understood that a manually operated choke valve is unnecessary because of the automatic choking action of the carburetor.

When a very rich mixture is desirable, as in starting a cold engine, the throttle valve is slidably opened manually, whereas the air valve will

remain closed due to the action of spring 38, until sufficient vacuum is developed to overcome the spring tension. The inrush of air is thus limited and the mixture will be very rich so that the engine will start without difficulty. A diagram of the starting position of the throttle valve 22 and the air valve 23 is shown in Figure 6.

As the engine speeds up, the increased suction acts upon piston 24 which opens up air valve 23 as far as flange 48 on piston rod 27 permits. Consequently the mixture decreases in richness, due to the admission of an ample supply of air, see the diagram shown in Figure 7, which shows driving at medium speeds or on a smooth road where comparatively little power is needed, and the engine suction is relatively high.

When full power is desired, the throttle valve 22 is fully opened. This will raise lever 45 to the position shown in the diagram of Figures 8 and 9 thus permitting the full opening of air valve 23 and also the closing of air valve 23 when the suction of the engine materially decreases. Assuming the engine is going at high speed with fully opened throttle, then the suction of the engine is so high that piston 24 will be fully raised and air valve 23 fully opened (see Figure 8). Decrease of engine speed for instance while climbing a hill with fully opened throttle valve materially decreases the suction of the engine so that spring 38 can force piston 24 downward and thus partly close the air valve 23. This action automatically increases the richness of the mixture at a time when most needed, a diagram showing the relative position of throttle valve 22 and air valve 23 under conditions just recited is shown in Figure 9.

The yielding connection of air valve 23 with lever 30 permits relative rotation between shaft 31 of valve 23 and lever 30 and thus prevents damage or breakage of lever 30 by backfiring.

Throttle valve 22 is actuated as customary by a push and pull element (not shown) ordinarily mounted on the steering gear or instrument board of the automobile. A wire connection also not shown interconnects said push and pull element with the operating lever 42 on shaft 41 of throttle valve 22.

Having thus described my invention:
What I claim is:

1. A carburetor comprising a body, mixing and fuel chambers in said body, a nozzle in the mixing chamber, a throttle valve in said mixing chamber, an air intake chamber, a valve in said air intake chamber, means to yieldingly hold said latter valve in closed position, means adapted to open said latter valve according to the speed of the engine and means for limiting opening of said latter valve according to the position of said throttle valve.

2. In a carburetor a throttle valve and a valve controlling the air intake, means to open said latter valve according to the speed of the engine, and coupling means between said throttle valve and said other valve for limiting the opening of said other valve to definite positions in accordance with the opening of said throttle valve.

3. In a carburetor a throttle valve and a valve controlling the air intake, means to open said latter valve according to the suction of the engine, and coupling means between said throttle valve and said other valve and preventing full opening of said other valve unless said throttle valve is sufficiently opened.

4. In a carburetor a throttle valve and a valve controlling the air intake, a cylinder communi-

cating with the intake side of the engine, a piston within said cylinder coupled with said air controlling valve, means to yieldingly close said latter valve, and means coupling said throttle valve with said air controlling valve and preventing full opening of said air controlling valve unless said throttle valve is sufficiently opened.

5 5. In a carburetor a throttle valve and a valve controlling the air intake, a cylinder communicating with the intake side of the engine, a piston within said cylinder having an extension coupled with said air controlling valve, a lever pivotally mounted on said carburetor connected with said piston and means on said extension of said 10 15 piston cooperating with said lever to limit the

upward movement of said piston and therewith the opening of said air controlling valve unless said throttle valve is sufficiently opened.

6. In a carburetor, a throttle valve, a valve controlling the air intake, a cylinder communicating with the intake side of the engine, a piston within said cylinder having a slotted extension, a lever coupled with said air controlling valve and slidably interengaged with said slotted extension of said piston and means coupled with said throttle valve and slidably interengaged with said extension of said piston for limiting the operation of said air valve by said piston in accordance with the position of said throttle valve.
